UNITED STATES PATENT OFFICE.

WILLIAM McCALLUM, OF YONKERS, NEW YORK, ASSIGNOR TO JOSEPH WILD & CO., OF NEW YORK CITY.

DESIGN FOR A CARPET-PATTERN.

Specification forming part of Design No. 5,552, dated February 20, 1872.

Specification describing a new and original Design for Carpet, invented by WILLIAM McCALLUM, of Yonkers, in the county of Westchester and State of New York.

The accompanying photographic illustration fully represents my new design.

This invention consists, first, of a new central figure, A, used on a carpet-design and made of rectangular form, and ornamented, as shown. The invention also consists of intertwining scroll B, arranged opposite the sides of the figure A, as shown.

I claim as my invention—

1. The design of a rectangular figure, A, on a carpet, as shown.
2. The design of the intertwining scroll B on a carpet, as shown.
3. The design for a carpet containing the figure A and scroll B, as shown.

WILLIAM McCALLUM.
